TILL LOCK WITH ALARM

Menachem Rotman, Philadelphia, Pa.

Application July 31, 1952, Serial No. 301,905
In Germany October 9, 1951

8 Claims. (Cl. 116—76)

1

The present invention relates generally to cash drawers or tills or the like and it relates more particularly to novel locking mechanism for such cash drawers or tills.

In their simplest form, cash depositories or tills for use in stores and the like are merely sliding drawers, installed beneath the counter, which can be opened by the store-keeper in receiving money or making change. On the other hand, cash depositories may consist of costly cash registers, which contain complicated adding, recording, tabulating and/or accounting mechanism, and which are much too expensive for the average small store-keeper. As a compromise between these extremes, it has heretofore been suggested to provide a cash drawer or till with means for manually recording individual transactions. It has also been suggested to provide such a cash drawer or till with mechanism for making an audible signal, such as a bell or buzzer, to warn the store-keeper against opening of the drawer by unauthorized persons. These conventional constructions have, however, proven inadequate and unsatisfactory.

Accordingly, it is an object of the present invention to provide a new and improved construction for cash drawers or tills or the like. Another object of the present invention is to provide a simple and inexpensive, yet effective, locking mechanism for such cash drawers. Still another object of this invention is to provide a self-contained lock which can be quickly and easily affixed to the outside of existing cash drawers. A further object of the present invention is to provide a locking device for tills which contains signalling mechanism for giving a loud and unmistakable audible signal, regardless of how slowly or carefully the drawer is opened by an unauthorized person.

However, since it is frequently desirable to lock the till (as, for example, when there are a number of customers in the store and the store-keeper is required to move a considerable distance away from the drawer or till) and since the use of a key for this purpose is not only awkward and time-consuming but also psychologically bad in making it appear to the customer that he is not being trusted, it is another object of this invention to provide a push button or other unobtrusive means for rendering the releasing mechanism inoperative and for thereafter making it necessary to use a key or the like to open the drawer. Still another object of the present invention is to provide means whereby the same push button which normally renders the releas-

2

ing mechanism inoperative can also be used to render the locking mechanism inoperative, so that the drawer remains unlocked when pushed in, for greater convenience when security is unnecessary, as for example, when the store has been closed and the day's receipts are being checked and tabulated.

A further object of this invention is to provide a till lock of the character described incorporating simple and inexpensive counting mechanism for recording the number of times the till has been opened and thereby giving some degree of protection against dishonest employees or the like.

15 Other objects and advantages of the present invention are apparent in the following detailed description, appended claims and accompanying drawings.

For the purpose of illustrating the invention, 20 there is shown in the accompanying drawings a form thereof which is presently preferred; it being understood, however, that the invention is not limited to the precise arrangements and instrumentalities shown and that the several parts 25 and elements can be variously arranged without departing from the spirit or essential attributes of this invention.

Referring to the accompanying drawings in which like reference characters indicate like parts throughout:

30 Figure 1 is a front elevational view of the novel till lock of the present invention.

Figure 2 is a side elevational view of the embodiment of Fig. 1.

Figure 3 is a vertical cross-sectional view, taken generally along the line III—III of Fig. 1.

Figure 4 is a rear elevational view looking generally in the direction of the arrows IV—IV of Fig. 3.

40 Figure 5 is a front elevational view of the working mechanism as it would appear if looking from inside the front plate of the housing generally in the direction of the arrows V—V of Fig. 3.

Figure 6 is a cross-sectional view taken generally along the line 6—6 of Fig. 5.

45 Figure 7 is a cross-sectional view taken generally along the line 7—7 of Fig. 5.

In one embodiment of the present invention, shown in Figs. 1—7, I may provide an open-back case or housing 1, the front panel of which has a window to receive the indicating portion of a conventional counter 2, which indicates the number of times the till is opened, as will be described hereinbelow. The front panel of the case 50 is also provided with openings, through which

extend a locking pin or button 3 and a key socket 4, to be described below.

The corners of the front panel are provided with holes to receive fastening bolts 5 which secure the case 1 to the front panel 51 of a drawer or till 52, which is slidably mounted within a structure, fragmentarily shown at 53, which may be a counter or display case or desk or cabinet or any other similar structure. The bolts 5 are provided with smoothly rounded rivet heads so that they cannot be removed from the outside of the case 1, when the drawer is closed. Alternatively, any other type of conventional fastening means, irremovable from the outside, may be employed, as for example, countersunk screws or bolts, rivets, toggle bolts, and the like.

Mounted on the front panel of the housing 1, is a pull handle 6 which is a hollow, open-bottom structure. Concealed within the interior 7 of the handle 6 is a lift-key 8 which is intended to be lifted manually so as to raise the latch 9 of the lock from the lowermost locking position shown in Figs. 1-5 (wherein it protrudes downward through a suitable opening in the bottom panel of the case 1 and into a corresponding socket formed in an extension piece 54 secured to the front of the structure 53, directly below the drawer 52) to retracted position within the case 1, and thereby to release the lock and permit the drawer to be opened, in a manner to be more fully described hereinbelow. Of course, a simple slidable bolt could be used in place of the spring-pressed yieldable latch 9, which is provided with an inwardly-directed curved camming surface, causing it to be momentarily retracted and thereafter automatically to snap closed in conventional manner when the till is closed.

Disposed inside the housing 1 is a generally U-shaped mounting frame or chassis 60 having a generally horizontal base 34, bolted or otherwise secured to the bottom panel of the housing, and a pair of spaced vertical plates 62 and 63; the front plate 62 being spaced slightly inwardly from the front panel of the housing. The lift-key 8, which is preferably formed of sheet-metal or the like, extends through an opening 64 in the front panel of the housing 1, and then bends downward, as at 8-a, in abutting relationship to the front plate 62. An extension piece 10, of generally rectangular cross-section, extends rearwardly from the portion 8-a of the lift-key, through elongated, aligned vertically-extending slots 65 and 66 in the plates 62 and 63, respectively, and through a similar slot 11 formed in the enlarged body 12 of the latch; the latch body 12 being disposed intermediate the plates 62 and 63, in vertically movable relationship thereto.

The free end 14 of the extension piece 10 protrudes inward somewhat beyond the plate 63 and is provided with a horizontal notch 13, giving a bifurcated construction.

Disposed within the notch 13 is the connecting-finger 15 of a movable member 16, which is slidably mounted on the rear side of the plate 63 by lower and upper pin-and-slot connections 17 and 67, respectively. Mounted at the upper end of the member 16 is a block 18, provided with a generally horizontal, slidable latch 20, which is urged inwardly by a leaf spring 19, so that its inwardly directed engaging end 21 (which has a downwardly-directed inclined camming surface) normally protrudes beyond the inner edge of the block 18, as shown in Fig. 4. In this position, the end 21 underlies and supports the end 22 of one arm 23 of a lever, which is pivotally mount-

ed, as at 24, on the rear side of the plate 63. The other (and longer) arm 25 of the lever is provided, near its end, with a pin 26, against which is seated the end of a coil spring 27, which is mounted on a rod 28, extending rearwardly from the plate 63 and supporting a bell 31 at its free end. On the pin 26 is mounted the hammer or clapper 30 of the bell. The spring 27 urges the lever counterclockwise in Fig. 4, so that the end 22 of the lever bears downward against the end 21 of the slidable latch 20, as described above. It is apparent that, as the lift-key 8 is lifted manually, it raises the movable member 16 and the several parts mounted thereon, and causes the protruding end 21 of the latch 20 to raise the end 22, thereby rotating the lever slightly clockwise against the pressure of the spring 27. During this clockwise rotation of the lever, the end 22 moves inward, as well as upward, until it clears the end 21 of the latch 20, whereupon the lever is pivoted violently counterclockwise, by the spring 27, causing the clapper 30 to strike a resounding blow against the bell 31 and resulting in a loud and unmistakable ring. Obviously, it is immaterial that the lift-key is lifted slowly and carefully (as might be the case with an unauthorized person), the force with which the clapper strikes the bell is always relatively the same.

The end 22 of the lever is provided with an upwardly-directed camming-surface, so that, after the lift-key is released and the member 16 moves back downward in a manner to be herein-after described, the downwardly-directed camming-surface of the end 21 contacts this upwardly-directed camming surface and causes momentary retraction of the latch 20 (against the pressure of its spring 19) to permit the latch 20 to clear the end 22 and return to its original position, shown in Fig. 4, wherein it is ready for another cycle of operation.

The latch body 12 is provided with an elongated vertical slot 33 into which extends a pin mounted on the front plate 62 so as to guide the latch body in vertical reciprocation. The latch body is also provided with an uppermost curved camming shoulder 35.

While the weight of the latch body 12 should be adequate to keep it in lowermost position, except when manually raised, and to return it to lowermost position after each lifting operation (to be herein-after described), I prefer to provide the latch body 12 with a helical spring 36, mounted on a post 68 secured to the plate 63; the free end of the spring 36 bearing against the camming shoulder 35 and positively urging the latch body 12 to lowermost position, as shown in Fig. 5.

As indicated in Fig. 3, the latch body 12 is provided with a pin 69 located just above the slot 11 and projecting forward so as to overlie the lift-key 8. Thus, upward manual movement of the lift-key, as described above, will also cause raising of the latch-body and latch 9. However, since the slot 11 has a greater vertical dimension than the extension-piece 10, the latch body is free to move upward and away from the lift-key (without causing raising of the member 16 or operation of the bell signal) during the momentary camming retraction of the latch 9, when the drawer is shut.

The latch body 12 has a lateral projection 37 which underlies the end of a downwardly-directed push-bar 38 of a conventional counter 39, which records each upward movement of the latch body and thus indicates (at 2 in Fig. 1) the number of times the drawer or till has been opened.

Referring now particularly to Figs. 5, 6 and 7, I provide a locking-unit 10 mounted intermediate the upper corners of the plates 62 and 63 and extending laterally appreciably therebeyond. The locking-unit 10 includes a body 71 of elongated, rectangular cross-section configuration, having a longitudinally-extending passageway 72 in which a bolt 40 is slidably positioned. A keyhole opening 73 extends inward from the front of the body and communicates with the passageway 72, which is generally rectangular in configuration but which, at that point, is provided with an arcuate notch 74 in its bottom wall to permit rotation of the key, to be described.

The body 71 is provided with another transverse opening intersecting the passageway 72, the front portion 75-a of said opening being circular in cross-section and the rear portion 75-b being rectangular in cross-section. To simplify manufacture, the rear surface of the body 71 may be formed as a separate plate, screwed or otherwise detachably connected to the remainder of the body, with the portion 75-b constituting a rectangular hole therein.

Slidably mounted within the passageway 72 is a bolt 40, normally urged inward (to the right in Fig. 5) by a compression spring 41 mounted at the outer end of the passageway and extending into a small socket formed in the outer end of the bolt.

The inner end of the bolt is bifurcated, with a longitudinal slot 44 intervening the upper portion 43 and the somewhat shorter lower portion 76 thereof.

The locking pin 3, which, for the most part, is circular in cross-section, is provided, at its inner end, with a generally rectangular locking-head 41a, which is undercut, as at 42, into a generally T-shaped configuration, to permit it to fit within the slot 44, and which is notched, as at 42-a, at the forward end of the undercut portion, along the outer edge thereof.

A leaf spring 77 is mounted on the rear of the body 71 and bears against the locking-head 41a so as normally to urge the locking pin forward and to maintain the locking-head 41a within the portion 75-b, with the undercut (but unnotched) portion 42 disposed within the slot 44 and bearing against the inner end wall 78 of the slot, so as to hold the bolt 40 in the retracted position shown in Fig. 5, wherein the free end of the portion 43 thereof is fully concealed within the body 71.

However, when the locking pin is manually pushed inward, it is shifted rearwardly from the solid line positions of Figs. 6 and 7 to the dash-dot line positions, against the pressure of the spring 77, and the notched portion 42-a comes into alignment with the slot 44.

This permits the bolt to move inward slightly, under the pressure of the spring 41, until the inner end wall 78 again seats against the recessed edge of the notched portion 42-a. In the last-mentioned position, the free end of the portion 43 protrudes inward beyond the body 71 and overlies the upper edge of the latch body 12 so as to prevent upward movement thereof from the lowermost locking position shown in Figs. 1-5.

Outwardly of the longitudinal slot 44, the bolt 40 is provided with a notch 46 formed by an outermost plane vertical wall 47 and an arcuate wall 48 extending (through approximately 90 degrees of arc) downwardly and inwardly from the upper end of the plane wall. The notch 46 is in line with the keyhole opening 73, so that,

upon insertion and rotation of a key or similar unlocking device 49, the tooth 50 of the key will, after moving along the arcuate surfaces 74 and 48, contact the plane wall 47 and, upon continued rotation of the key, shift the bolt laterally outwardly to its original retracted position. As the bolt thus moves outward, the spring 77 again shifts the locking pin 3 forwardly to its original position, wherein the portion 42 comes within the slot 44 and automatically locks the bolt in retracted position.

A notch 45 is formed in the side edge of the latch body 12 slightly below the upper edge thereof, the notch being in line with the portion 43 of the bolt 40 when the latch body is in its uppermost position. Accordingly, if the latch body 12 is first raised (by lifting the lift-key 8) and the locking-pin 3 is then pushed, the bolt will be released so that its end 43 will be shifted into the notch 45, thereby locking the latch in raised inoperative position until the key is inserted and turned to retract the bolt 40 in the manner described above. In this manner, it is possible to maintain the locking mechanism in open position when the store is closed and the receipts are being calculated, and at other times when security is not important.

In other words, the locking-pin 3 can be used to lock the latch 9 either in lowermost locking position or in uppermost retracted inoperative position, depending on whether the lift-key 8 is in its normal lowermost position or in manually raised position when the locking-pin is pushed in. In either case, insertion and operation of the key 49 in the manner described, will free the latch 9 for normal operation, wherein it is raised to retracted unlocking position upon manual raising of the lift-key 8, and wherein it is moved back to lowermost position by spring action upon release of the lift-key, and wherein it automatically locks within the socket of the extension piece 54 (following momentary camming retraction thereof) when the drawer or till is pushed inward to closed position, all in the manner more fully described hereinabove.

The key 49 could, of course, be constructed in any other suitable form, including, for example, a form which would cause retraction of the bolt 40 upon simply being pushed inward (through conventional camming action) in place of the rotational action illustrated.

While, for simplicity, only a single lift-key is shown, it is possible to provide a plurality (for example five or six) of such lift-keys, with conventional mechanism, well known in the art, for rendering the latch-raising means operative only when the correct, pre-determined combination of two or more of the lift-keys is manually raised, so as to give added protection against opening of the till by unauthorized persons not in possession of the correct combination.

From the foregoing description, it is apparent that the novel lock of the present invention is a simple, inexpensive, yet dependable device, which can readily be affixed to pre-existing cash drawers or tills, which gives a clear and unmistakable ring or other audible warning signal each time the drawer is opened, which includes a push-button or other similar part enabling the store-keeper unobtrusively to secure the latch mechanism in locking position or optionally in retracted inoperative position, and which includes means, separate from the push-button, for releasing the latch mechanism for normal operation, wherein it is manually raised to unlocking position and

automatically returns to locking position, securing the drawer when the latter is pushed inward to closed position.

The present invention may be embodied in other forms, those described herein being merely illustrative and not restrictive, and, accordingly, reference should be made to the appended claims, rather than to the foregoing description, as indicating the scope of the invention.

Having thus described my invention, I claim as new and desire to protect by Letters Patent:

1. In a lock constructed and arranged to be affixed to cash drawers and the like, a movable latch; means normally urging said latch to extended locking position; a lift-key or the like for manually shifting the latch to retracted disengaged position; a movable bolt located within the housing and shiftable into extended position blocking movement of the latch; a spring urging said bolt toward latch-blocking position; means for releasably holding the bolt in retracted position, said last-mentioned means including a manually operable locking-pin constructed and arranged normally to prevent spring-actuated movement of the bolt but being shiftable to bolt-releasing and latch-blocking position; means, separate from the locking-pin and including a removable key or the like, for returning the bolt to retracted position thereby freeing the latch, and means for sounding an audible signal each time the latch is shifted to retracted position, said last-mentioned means comprising a bell or the like and trip-hammer mechanism including a lever pivoted intermediate its ends and having a bell clapper mounted at one end and a spring urging the lever to bell-striking position, a slidable member connected to, and linearly movable with, the lift-key and carrying a spring-extended retractable engaging latch constructed and arranged normally to underlie the other end of the lever so as to cause tilting of the lever against the pressure of the lever spring during the early portion of the retracting movement of the latch, the end of the lever slipping off the engaging latch and permitting the spring-actuated bell-striking opposite tilting of the lever upon continued retraction of the latch.

2. A construction according to claim 1 wherein the latch is provided with a recess which is in line with the bolt when the latch is in retracted position, whereby the latch can also be maintained in retracted disengaged position by first raising the lift-key to retract the latch and then pushing the locking-pin to release the bolt and to enable the end of the bolt to enter the recess.

3. A construction according to claim 1 wherein the lift-key is provided with an extension piece passing through an elongated slot in the body of the latch with the free end thereof connected to the slidable member and wherein the end of the engaging latch is provided with a camming surface enabling the engaging latch to be momentarily retracted by the adjoining end of the lever upon the return movement of the slidable member so as to enable the engaging latch to clear the end of the lever upon said return movement.

4. In a lock constructed and arranged to be affixed to cash drawers and the like, a movable

latch; means normally urging said latch to extended locking position; a lift-key or the like for manually shifting the latch to retracted disengaged position; a movable bolt located within the housing and shiftable into extended position blocking movement of the latch; a spring urging said bolt toward latch-blocking position; means for releasably holding the bolt in retracted position, said last-mentioned means including a manually operable locking-pin constructed and arranged normally to prevent spring-actuated movement of the bolt but being shiftable to bolt-releasing and latch-blocking position; means, separate from the locking-pin and including a removable key or the like, for returning the bolt to retracted position thereby freeing the latch, the bolt being an elongated slidable member having one end bifurcated, with a longitudinal slot extending inward an appreciable distance therealong, the locking-pin being disposed generally at right angles to the bolt with an intermediate portion of reduced thickness extending through the slot, said intermediate portion of the locking-pin being longer than the thickness of the bolt and being notched at one end, so that, in one position of the locking-pin, the end-wall of the bolt slot bears against the unnotched part whereby the bolt is held in retracted position, while in the other position of the locking-pin, the notched end is within the slot whereby the bolt is free to move to extended latch-blocking position under the action of its spring.

5. A construction according to claim 4 wherein the locking-pin is provided with a spring normally urging it to extended position wherein the unnotched part of its reduced-thickness intermediate portion is within the slot of the bolt and wherein manual inward pressure on the locking-pin shifts it to bolt-releasing position so as to block the latch.

6. A construction according to claim 5 wherein the bolt is provided with a key-receiving opening whereby it can be shifted back to retracted position, against the pressure of its spring, after it has moved to extended latch-blocking position following operation of the locking-pin.

7. A construction according to claim 6 wherein the bolt, when in extended position, normally maintains the latch in extended locking position.

8. A construction according to claim 7 wherein the latch is provided with a recess which is in line with the bolt when the latch is in retracted position, whereby the latch can also be maintained in retracted disengaged position by first raising the lift-key to retract the latch and then pushing the locking-pin to release the bolt and to enable the end of the bolt to enter the recess, thereby blocking movement of the latch until retraction of the bolt.

MENACHEM ROTMAN.
